UNITED STATES PATENT OFFICE.

LOUIS A. WILCOX, OF CHATHAM, ONTARIO, CANADA, ASSIGNOR OF ONE-HALF TO
ALBERT H. ARMSTRONG, OF CHATHAM, ONTARIO, CANADA.

LIFE-BOAT.

1,175,393.

Specification of Letters Patent. Patented Mar. 14, 1916.

Application filed March 11, 1915. Serial No. 13,803.

To all whom it may concern:

Be it known that I, LOUIS A. WILCOX, a British subject, residing at Chatham, county of Kent, Province of Ontario, Dominion of Canada, have invented a certain new and useful Improvement in Life-Boats, and declare the following to be a full, clear, and exact description of the same, such as will enable others skilled in the art to which it pertains to make and use the same, reference being had to the accompanying drawings, which form a part of this specification.

My invention relates to life boats, shown in the accompanying drawings and more particularly described in the following specification and claims.

One of the objects of my invention is to provide an inclosed boat in which the occupants may be kept dry, protected from the wind, and thereby relatively comfortable.

A further object of the invention is to provide a pendent platform located within the inclosing outer shell of the boat upon which the passengers may be seated, the construction being such that it will not roll with the outer shell upon motion being imparted to the latter by the waves.

A still further object is to provide means adapted to supply air and ventilation to the chamber in which the passengers are housed, and to automatically close the air and ventilation tubes against the entry of water in the event of a wave crest rising above the open end of the tubes.

A still further object is to provide for the admission of air from the bulkheads into the chamber housing the passengers, should it become necessary to temporarily supply them with air pending the delivery of fresh air through the ventilating tubes.

A further object is to provide for the admission of light to the passenger chamber, and means for sealing the hatchway door, into the chamber against the admission of water.

A further object is to provide suitable storage compartments for food and water beneath a centrally arranged longitudinal seat carried by the pendent platform.

Other advantages and improvements will hereafter appear.

In the drawings accompanying this specification, Figure 1, is a plan view of the boat. Fig. 2, is a horizontal central sec-

tional view of the same. Fig. 3, is a longitudinal vertical sectional view through the boat showing parts in elevation. Fig. 4, is a central cross sectional view. Fig. 5, is a fragmentary detail in section, showing the locking means for securing the hatchway door in position. Fig. 5^a, is an inverted fragmentary view of the shell and locking hook. Fig. 6, is a detail view of one of the automatic valves for controlling the admission and delivery of air through the air and ventilating tubes.

Referring now to the letters of reference placed upon the drawings, A, denotes the outer shell of the boat, preferably constructed of sheet metal, comprising a central cylindrical compartment A', to which are fitted cone-shaped sheet metal ends A², A².

B, and B', are tubular members supported at their outer ends by the cone-shaped walls A², A², to which they are engaged.

C, and C', are bulkheads through which the inner ends of the pipes B, and B', project and to which they are bolted, forming with the ends A², A², air tight compartments to insure buoyancy.

D, is a pendent platform having side walls D' concentric with the outer shell A;—its end walls D², being journaled on the ends of the inwardly projecting pipes B, B', which serve as supporting trunnions. D³, denote end frames secured to the pendent platform and clamped to the end of the projecting end of the ventilating tubes housed within the pipes.

E, E', denote ventilating tubes respectively sleeved within the pipes B, B', and opening into the central chamber A';—their ends extending upwardly to a point preferably above the top of the boat.

F, F', indicate stuffing boxes sleeved on the ventilating tubes, having a screw threaded engagement with the pipes B, B',—upon adjusting which a water tight joint may be had between the ventilating tubes and the pipes B and B'.

G, G', denote valves controlling the admission and passage of air through the ventilating tubes, adapted to automatically close against the entry of water into the ventilating tubes by the action of the floats H, H, which rise and fall with the waves. The floats H, H, are provided with an adjustable stem H', engaging a slotted rock-

ing arm H^2 , pivoted in the standards E^2 , extending upwardly from the ventilating tubes.

5 G^2 , is a valve stem projecting upwardly from the respective valves G , G' , engaging the other slotted arm of the rocking lever H^2 .

10 G^3 , is a valve guide directed downwardly from the valve G , G' , into the tubes and provided with openings G^4 , through which air passes to the ventilating tubes upon the valve being raised from its seat.

15 E^3 , denotes a lug formed on the standard E^2 , to limit the upward movement of the valve.

I , is a valve controlling the delivery of air from the bulkheads C , C' ,—it being obvious that air may also be admitted through the valve into the bulkheads.

20 J , denotes a sliding trap or hatch door.

J' , indicates a glazed window through which light may be admitted to the central inclosed chamber.

25 J^2 , are guides to receive the frame of the sliding hatch door.

J^3 , is a suitable gasket carried by the door to insure a water tight joint.

30 K , designates a swinging latch carried by the door having suitable operating handles K' , by which it may be rocked.

35 K^2 , indicates a pin projecting inwardly from the wall of the central chamber engaged by the latch.

L , is a central longitudinally arranged seat 35 mounted on the floor of the pendent platform upon which the passengers may sit back to back. The cover of the seat is hinged and below the cover is provided convenient locker room for storing water, food, and 40 other supplies L' .

Having indicated the several parts by reference letters the construction of the boat will be readily understood.

Upon the passengers entering the boat 45 through the opening provided, the hatch or trap door J , is slid into place and secured by means of the swinging latch K ;—the occupants resting upon the seat secured to the pendent platform D . In the event of the 50 outer shell or cylinder rolling, due to the action of the wind and waves, the passengers will not be affected, it being obvious that the pendent platform D , will not rotate with the outer shell. It will also be 55 apparent that air and ventilation are provided by means of the pipes, E , E' , and that the valves G , G' , (adapted to be seated in the open ends of the ventilating tubes) will be held constantly open by the weight of the

float chamber H , acting upon the rocking lever H^2 , with which the valve stem is connected;—unless the waves should rise sufficiently to endanger flooding the chamber with water through the open end of the ventilating pipes, in which event the floats will automatically close the valves against the entry of water,—the valves immediately opening again upon the crest of the waves receding. Should an emergency arise making it necessary to admit other air into the 70 chamber, the valves I , I , may be opened to deliver air from the bulkheads;—or air may be admitted to the bulkheads through said valves.

Having thus described my invention what 75 I claim is:—

1. In a boat, a shell having cone shaped ends, bulkheads arranged at the inner ends of said cone shaped ends to divide the shell into end air compartments and an intermediate passenger chamber, tubular members connected at their ends to the apices of the cone shaped ends and extending through the bulkheads into the passenger chamber, ventilating tubes extending through said 80 tubular members and at their inner ends opening into the passenger chamber, the outer ends of the ventilating tubes extending upwardly, valves connected to the ventilating tubes, means for automatically closing the valves to prevent the entry of water through the ventilating tubes into the passenger chamber upon submersion of the outer ends of the tubes, and a pendent platform suspended from the inner ends of said tubular members.

2. In a boat, a shell having cone shaped ends, bulkheads located in the shell dividing the shell into end air compartments and an intermediate passenger chamber, tubular members connecting the outer ends of the cone shaped ends and the respective bulkheads and leading into the passenger chamber, and valved ventilating tubes extending into the passenger chamber through said 100 tubular members and on which the shell is journaled, the valves of the ventilating tubes being arranged so as to automatically close the ventilating tubes when the latter are submerged and to open when the tubes project out of the water, and valves in the bulkheads.

In testimony whereof, I sign this specification in the presence of two witnesses.

LOUIS A. WILCOX.
